(57) **CLAIM**

We claim the ornamental design for a frame for window air conditioner, as shown and described.

DESCRIPTION

FIG. 1 is a front perspective view of a frame for window air conditioner showing our new design;

FIG. 2 is a rear perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is an enlarged view of portion 9 shown in FIG. 1; FIG. 10 is another enlarged view of portion 9, showing the frame for window air conditioner in an alternate configuration; and,

FIG. 11 is a front perspective view of the frame for window air conditioner, shown in an environment of use.

The dot-dot-dash broken lines shown in FIGS. 1, 9 and 10 indicate the enlargement area that form no part of the claimed design. The evenly-spaced broken lines and the dot-dot-dash broken line in FIG. 11 respectively illustrate an environmental structure and a boundary of a view with environment that form no part of the claimed design.
